UNITED STATES PATENT OFFICE

107,631

DESIGN FOR A DRESS

Mercedes Hall, New York, N. Y.

Application November 18, 1937, Serial No. 72,979

Term of patent 3½ years

To all whom it may concern:

Be it known that I, Mercedes Hall, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

The characteristic feature of my design resides in the alternate combination of shell tucking and tucks particularly arranged, as shown.

I claim:

The ornamental design for a dress, substantially as shown and described.

MERCEDES HALL.
